UNITED STATES PATENT OFFICE.

BARNES NEVILLE WALLIS AND CHARLES DENNISTON BURNET, OF WESTMINSTER, OF
LONDON, ENGLAND, ASSIGNEES TO AIRSHIP GUARANTEE COMPANY, LIMITED, OF
LONDON, ENGLAND.

LIGHTER-THAN-AIR AIRCRAFT.

Application filed December 17, 1925, Serial No. 75,981, and in Great Britain January 9, 1925.

This invention relates to lighter-than-air aircraft.

Much attention has, in recent years, been devoted to the problem of increasing the speed of airships, and, in order that this may be economically accomplished, it is desirable to introduce devices for reducing their head resistance. The principal method of obtaining improvement in the latter respect has been to make the hull of the airship of a so-called streamline shape, and considerable data are now available showing the general form that should be followed in designing the lines of the body or hull of the airship or aerostat.

For example, it is known that a body having a ratio of overall length to maximum diameter of $4\frac{1}{2}$ or 5 to 1 will offer as low a resistance to propulsion through the air as any ship yet produced, provided the following proportions are generally maintained; (a) That the head or front portion should be approximately two diameters long, at which distance from the nose the maximum diameter of the body should occur, and should consist of a semiprolate ellipsoid that is to say the solid formed by the rotation of a semiellipse about its major axis; and (b) that the tail or after portion should be approximately $2\frac{1}{2}$ or 3 diameters long measured from the place at which it joins the head portion.

Such a form having been obtained, it is found, however, that the shape appears to be too sensitive to external disturbances when reproduced on a full sized ship.

It must be understood that at the present time it is customary to locate the main loads of lighter-than-air aircraft such as the control, passenger, and engine cars at various points along or beneath the hull, and as they project beyond the contour of the airship or aerostat they form protuberances which interfere with the streamline flow around and along the hull or body, and thus set up discontinuous flow and turbulence.

This turbulence is most serious when originated in the region of the head portion, as is the case when the cars, or other causes of turbulence, are situated forward of the maximum diameter of the ship.

Further, it is found that the lower the resistance of the bare hull or body, the more serious do such disturbances become so that

in the past it may even have been preferable to construct a hull actually having a higher head resistance in itself, in order that the total resistance of the ship when fitted with cars might be, in the aggregate, less than that of a sensitive shape when fitted with an identical arrangement of cars.

According to the present invention the front part of an airship, or other lighter-than-air aircraft of torpedo-like configuration, is kept, up to the maximum diameter thereof, free or substantially free of external protuberances, such as cars, struts, wiring, etc. To this end the main loads, such as the observation, passenger, and engine cars are either wholly located within the outer cover of the airship or aerostat so that they do not protrude beyond the contour thereof or else they are located abaft the maximum diameter of the ship, where the turbulence set up is not of a serious nature. Alternatively, a combination of these two methods may be employed, so that the ship or aerostat is kept free or substantially free of protuberances up to a point abaft the maximum diameter thereof.

It has been found that by adopting such an arrangement of the main loads and/or external protuberances the total resistance is very considerably reduced; it may in certain cases be reduced by as much as 30%. Furthermore, this disposition of the main loads within the external streamline or contour, or abaft the maximum diameter of the airship or aerostat, also enables the most approved streamline configuration to be adopted, while retaining the advantages of reduced head resistance, sensitiveness to control and navigability which result from the use of a fine streamline shape.

In the case of a rigid airship the main protuberances, such as the observation or control car and the passenger and engine cars, may be located within the contour or outer streamline of the ship, or certain of the main loads, such as the observation and passenger cars, may be located within the outer streamline of the ship, while the engine cars may be located abaft the maximum diameter of the airship in the zone of negative pressure. The ship may be of streamline configuration and have a length to diameter ratio of $4\frac{1}{2}$ or 5 to 1 or as may be found desirable. The nose of the ship up

to the first transverse frame may itself be employed as an observation and/or control car, as also for the purpose of enabling the passengers to enter and leave the airship.

5 In order that the said invention may be clearly understood and readily carried into effect the same will now be described more fully with reference to the accompanying drawing, in which:—

10 Figure 1 is a part sectional elevation of a rigid airship constructed according to the present invention.

15 Figure 2 is a cross section of part of one side of the airship the section being taken in the way of the coaches.

20 Figure 3 is a part sectional plan view of Figure 1 showing the front portion of the airship up to the maximum diameter thereof.

25 A is the outer cover or enveloping surface of the airship. B, B are the longitudinal girders and B¹, B¹, the transverse frames. C is the mesh wiring which encloses the gas bags the latter being located as is customary between each pair of transverse frames B¹, B¹, the mesh wiring being preferably of the kind described in English Patent No. 233,020 in order to allow tangential loading to be resorted to. D is the mesh wiring on the face of each of the transverse frames, and E is cord netting located transversely of the airship between each pair of gas bags, the cord netting being connected to the frames by flexible steel cables E¹, E¹. F, F are the coaches which are preferably suspended from the framework of the airship and have their parts constructed and arranged in the manner described in our co-pending English application No. 238,981. It will be observed that the coaches are located entirely within the streamline or outer enveloping surface A of the airship. G, G are corridors located on each side of the airship and establishing communication between a compartment H at the nose of the airship and the passenger coaches. It will be observed that staircases I, I are carried by the suspended coaches F, F and that the corridors G, G on each side of the airship give access to the said staircases. The corridors G, G are preferably also suspended from the framework of the airship in the manner described in the specification of our English Patent No. 233,021. The corridors G, G by which access is obtained to the passenger coaches F, F extend beyond the coaches (see Figure 1) so as to allow the crew to have access to all parts of the airship, and additional passages may also be provided in the interior of the 50 transverse frames as described in our English patent specification No. 233,021. The compartment H at the nose of the airship

not only allows the passengers to enter and leave the airship through a transversely disposed corridor h, (see Figure 3) which 65 establishes communication between the exterior and the corridors G, G, but is also employed as an observation and control car; observation posts being provided, for example at the points h, h¹. In the arrangement shown, the compartment H is located between an auxiliary frame H¹ situated between the nose of the airship and the first main transverse frame B¹. The maximum diameter of the airship occurs at the point 75 X—X, and it will be observed that the only protuberances beyond the streamline or outer envelope of the airship are the engine cars L, L and the usual control fins K, K, and that these are located beyond the maximum 80 diameter thereof. Consequently, the airship up to the maximum diameter thereof is kept entirely free of the usual external protuberances, such as the control or observation station, the coaches for the passengers and 85 crew, and the engine cars.

The transverse and longitudinal frames may be constructed in the manner described in our English Patent No. 233,021. Furthermore, and in order to avoid distortion 90 of the contour or external streamline due to flapping of the outer cover, which flapping as is well known, results usually from deterioration in the dope used to stiffen the same, or slackening of the lacing by which the outer cover is held taut, or partly due to one or other of these causes, the outer cover may be maintained taut by inflating or distending the same by air pressure as described in our co-pending application Serial No. 1901 100 of 1925. This method of keeping the outer cover taut also has the advantage of ventilating the airship without necessitating the use of external protuberances, while the gas pressure of the internal gas bags may also 105 be relieved by valves which do not protrude beyond the contour or external streamline of the airship.

What we claim and desire to secure by Letters Patent of the United States is:—

An airship comprising a front portion consisting of a semi-prolate ellipsoid approximately 2 diameters long at which distance from the nose the maximum diameter of the airship occurs, and a rear portion 115 which is approximately 2½ or 3 diameters long measured from the place where it is joined to the front portion, said front portion up to the maximum diameter of the airship being free or substantially free from 120 external protuberances.
